UNITED STATES PATENT OFFICE.

WILLIAM H. LYNCHARD, OF COUNCIL BLUFFS, IOWA.

DESIGN FOR A BADGE.

SPECIFICATION forming part of Design No. 33,062, dated August 14, 1900.

Application filed June 29, 1900. Serial No. 22,080. Term of patent 3½ years.

To all whom it may concern:

Be it known that I, WILLIAM H. LYNCHARD, a citizen of the United States, residing at Council Bluffs, in the county of Pottawattamie and State of Iowa, have invented and produced a new and original Design for Badges, of which the following is a specification, reference being had to the accompanying drawings, forming part thereof, in which—

10 Figure 1 is a front elevation, and Fig. 2 a vertical central section.

As shown in the said drawings, my badge consists of a representation of the palm of a hand, as shown at A. Running from the tip 15 of the thumb to the tip of the little finger is a scroll or band B, adapted to contain a suitable inscription, and immediately under the hand is a smaller scroll or cornucopia C, also adapted to contain an inscription. Running 20 from one scroll to the other, as though

it were behind the hand A, is an ornamental garland D.

The essential or leading feature of my design is the hand with the scrolls for containing inscriptions, arranged substantially as 25 shown.

Having described my invention, what I claim as new, and desire to secure by Letters Patent, is—

The design for a badge, as herein shown 30 and described.

In testimony whereof I hereby sign my name to this specification, in the presence of two subscribing witnesses, this 21st day of June, 1900.

WILLIAM H. LYNCHARD.

Witnesses:

D. E. STUART,
THOMAS BOWMAN.
